UNITED STATES PATENT OFFICE.

MICHAEL R. ZAHNISER AND MONTGOMERY J. ZAHNISER, OF WASHINGTON, PENNSYLVANIA.

FOUNDATION FOR DERRICKS.

964,140.

Specification of Letters Patent. Patented July 12, 1910.

Application filed April 11, 1910. Serial No. 554,693.

To all whom it may concern:

Be it known that we, MICHAEL R. ZAHNISER and MONTGOMERY J. ZAHNISER, citizens of the United States, residing at Washington, in the county of Washington and State of Pennsylvania, have invented certain new and useful Improvements in Foundations for Derricks; and we do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in derrick foundations and the object in view is to produce a simple and efficient device of this nature dispensing with bolts and threads in the corner joints and providing a smooth socket easily adjusted and also providing a sectional ring for holding the fitting in position and affords means for allowing the brace rods to draw the derrick together in such a manner that the tension will be equally distributed upon the different parts.

Our invention comprises various details of construction, combinations and arrangements of parts which will be hereinafter fully described and then specifically defined in the appended claims.

Our invention is illustrated in the accompanying drawings, in which:—

Figure 1 is a top plan view of a derrick foundation embodying the features of our invention, and Fig. 2 is an edge view.

Reference now being had to the details of the drawings by letter, A designates a top saddle casting having a socket for the reception of the leg of a derrick and adapted to be fastened thereto in any suitable manner, and B is a double saddle which permits the pipes D and E to lie at right angles to each other and hold the same in such positions.

C designates a base saddle upon which the lower sill or pipe D rests, the adjacent faces of said saddles B and base C being concaved upon their adjacent faces to conform to the pipe or sill D which they engage. The bolts F pass through registering apertures formed in the flanges of the saddles and nuts F' upon the bolts serve to

hold the saddles securely against the tubes engaged thereby. Positioned underneath the base saddle is a casting H having fastened thereto by threaded connection section D' which is also secured to the base saddle in any suitable manner.

It will be noted that the pipes K which are positioned intermediate the end pipes E are held by a single saddle O resting upon the pipes D having their upper edges concaved for the reception of the pipes K, and a U-shaped strap or rod Q passes underneath the pipe or sill D and passes through apertures in the bars R, nuts S being fastened upon the ends of said strap and which, when tightened, serve to draw the pipes together and hold the same in adjusted positions.

From the foregoing, it will be noted that, by the provision of a foundation made in accordance with our invention, a simple and efficient apparatus is afforded which will securely hold the corners against unusual strain which might come upon the same incident to the use of the derrick held thereby.

What we claim to be new is:—

1. A derrick foundation comprising a plurality of sills spaced apart, double saddle castings mounted thereon, sills supported upon said saddles, socket saddles resting upon the top sills, and bolts clamping said saddles against the sills.

2. A derrick foundation comprising two under sills spaced apart, base saddles upon which said sills rest, double saddles resting upon said sills and conforming to the contour of the latter, a second series of sills resting in concaved portions of the double saddles, top saddles engaging said second series of sills and provided with sockets adapted to receive and hold the upright frames of the derrick, and means for holding the saddles in clamping relation to the sills.

3. A derrick foundation comprising two under sills spaced apart, base saddles upon which said sills rest, double saddles resting upon said sills and conforming to the contour of the latter, a second series of sills resting in concaved portions of the double saddles, top saddles engaging said second series of sills and provided with sockets adapted to receive and hold the upright frames of the derrick, said saddles having laterally projecting flanges which are pro-

vided with registering apertures, retaining bolts passing through said registering apertures, and means for holding the saddles in clamping relation with the sills.

5 4. A derrick foundation comprising two under sills spaced apart, base saddles upon which said sills rest, double saddles resting upon said sills and conforming to the contour of the latter, a second series of sills 10 resting in concaved portions of the double saddles, top saddles engaging said second series of sills and provided with sockets adapted to receive and hold the upright frames of the derrick, said saddles having 15 laterally projecting flanges which are pro-

vided with registering apertures, retaining bolts passing through said registering apertures, means for holding the saddles in clamping relation with the sills, a support underneath the base saddle, and a pipe connecting the latter with said base. 20

In testimony whereof we hereunto affix our signatures in the presence of two witnesses.

MICHAEL R. ZAHNISER.
MONTGOMERY J. ZAHNISER.
